UNITED STATES PATENT OFFICE

SAUL L. LACHTER, OF IRVINGTON, NEW JERSEY

DESIGN FOR AN EYEGLASS CASE

Application filed April 28, 1932. Serial No. 43,648. Term of patent 14 years.

To all whom it may concern:

Be it known that I, SAUL L. LACHTER, a citizen of the United States, residing in the town of Irvington, in the county of Essex and State of New Jersey, have invented a new, original, and ornamental Design for an Eyeglass Case, of which the following is a specification, reference being had to the accompanying drawing, forming part thereof.

In the drawing,

Fig. 1 is a top plan view of an eyeglass case showing my new design;

Fig. 2 is an under plan view; and

Fig. 3 is an end elevational view of the same.

I claim:

The ornamental design for an eyeglass case, as shown.

SAUL L. LACHTER.
